Primary Examiner—Robin Webster*Assistant Examiner*—Karen E. Patterson*(74) Attorney, Agent, or Firm*—Fitch, Even, Tabin & Flannery(57) **CLAIM**

The ornamental design for a spider web shaped pasta, as shown and described.

DESCRIPTION

FIG. 1 is a perspective view of a spider web shaped pasta showing my new design;

FIG. 2 is a front elevational view thereof, the rear elevational view being a mirror image;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view of a spider web shaped pasta showing a second embodiment of my new design;

FIG. 8 is a front elevational view thereof, the rear elevational view being a mirror image;

FIG. 9 is a left side elevational view thereof;

FIG. 10 is a right side elevational view thereof;

FIG. 11 is a top plan view thereof;

FIG. 12 is a bottom plan view thereof;

FIG. 13 is a perspective view of a spider web shaped pasta showing a third embodiment of my new design;

FIG. 14 is a front elevational view thereof, the rear elevational view being a mirror image;

FIG. 15 is a left side elevational view thereof;

FIG. 16 is a right side elevational view thereof;

FIG. 17 is a top plan view thereof; and,

FIG. 18 is a bottom plan view thereof.
